UNITED STATES PATENT OFFICE.

FREDERIC HENRY EHNTS, OF PHILADELPHIA, PENNSYLVANIA, ASSIGNOR, BY MESNE ASSIGNMENTS, TO THE FIFTH AVENUE BANK OF NEW YORK, OF NEW YORK, N. Y., A CORPORATION OF NEW YORK.

WASHING MACHINE.

Application filed March 23, 1921, Serial No. 454,744.

To all whom it may concern:

Be it known that I, FREDERIC HENRY EHNTS, a citizen of the United States, residing at Philadelphia, in the county of Philadelphia and State of Pennsylvania, have invented certain new and useful Improvements in Washing Machines, of which the following is a specification.

My invention relates to new and useful 10 improvements in washing machines, and more particularly to machines for washing, dyeing or liquid-treating fabrics and similar material.

The invention consists in the improvements to be more fully described hereinafter, and the novelty of which will be particularly pointed out and distinctly claimed.

I have fully and clearly illustrated my invention in the accompanying drawings to be 20 taken as a part of this specification, and wherein—

Figure 1 is a view in end elevation of a preferred embodiment of the invention, certain internal parts being shown in dotted 25 lines;

Fig. 2 is a view in side elevation of the structure shown in Fig. 1, certain internal parts being shown in dotted lines, and part 30 of the casing or framework being broken away to expose a portion of such internal parts in full lines;

Fig. 3 is a section on the line 3—3 of Fig. 2;

Fig. 4 is a section on the line 4—4 of Fig. 2;

Fig. 5 is a longitudinal section on the line 5—5 of Fig. 1;

Fig. 6 is a transverse section through a modified form of cylinder or receiver in 40 which the material to be treated is placed;

Fig. 7 is a further modification of the cylinder in which the material to be treated is placed, and

Fig. 8 is a detail view of one of the elements of the invention.

Referring to the drawings by characters of reference, 1 designates generally a framework consisting of corner standards 2 upon which the machine is supported, said standards being connected and braced by transverse tie members 4 at the sides of the machine, and similar tie members 3 at the ends of the machine whereby a rectangular framework is provided. Supported by the

said corner standards and transverse members 3 and 4, is a receptacle 5, preferably rectangular in plan, and having vertical side and end walls 6, 7, and a curved bottom wall 8. In the embodiment illustrated, this receptacle is liquid tight, and is adapted to contain the treating liquid.

Within the receptacle 5 is supported a receiver or container adapted to contain the material to be treated. In the preferred embodiment shown, this receiver consists of a 65 perforated cylindrical drum or shell 9 arranged to turn on a horizontal axis, and having its ends closed by means of imperforate circular heads 10. The shell 9 is provided with an opening 11 through which the 70 stock or material to be treated is charged into, and discharged from, the receiver, said opening being provided with a suitable closure, preferably consisting of arcuate doors 12, hinged, as at 13, at the longitudinal 75 edges of the opening 11, the curve of said closures preferably being such that when closed said closures constitute a continuation of the cylindrical shell of the receiver, as clearly shown in Figs. 2 and 3. The 80 doors or closures 12 are held in closed position by any suitable form of latch 14. The receiver is provided with suitable bearings whereby it may be revolved or turned upon its horizontal axis, and for this purpose one 85 end or head 10 of the receiver is provided with a bearing member 15 carrying a trunnion 16 removably seated and adapted to turn in a bearing socket 17 carried by a plate 18, rigidly connected, in any suitable manner, to an end wall of the receptacle 5. The bearing 17 is preferably open at its upper portion, as at 19, so as to permit ready removal of the trunnion 16 therefrom, when it is desired for any reason to remove the receiver from the receptacle. The opposite head of the receiver from that just described 90 is provided with a bearing member 20, the same being rigidly connected to the said head, and having a central polyfaced socket 100 21 receiving a correspondingly formed polyfaced head 22 fixed upon a horizontal driving shaft 23 mounted in a suitably packed bearing 24 in the end wall 6 of the receptacle 5. The bearing 24 is packed so as to 105 prevent leakage of the liquid contents of the receptacle. Externally of the receptacle 6, the shaft 23 is enclosed within a casing 25

having a bearing 26 in which one end of said shaft turns, and loosely mounted upon said shaft within said casing is a bevel gear 27, the hub of which is provided with a clutch element 28. Mounted on the shaft 23, adjacent the hub of the gear 27, is a clutch element 29, the same being keyed or splined to the shaft in a well-known manner, for example, by a pin extending through said element 29 and a longitudinal slot in said shaft. The clutch element 29 is provided with a clutch face 30 adapted to cooperate with the clutch element 28 to lock the gear 27 to the shaft when said elements 28 and 29 are in engagement. The element 29 is provided with an annular groove 31 which is engaged by a yoke 32 operatively connected to a rock-shaft 33 mounted in a suitable bearing 33^a in the casing 25, upon the outer end of which rock-shaft is rigidly secured an operating lever 34, by means of which the clutch member 29 may be thrown into and out of engagement with the clutch member 28 on the gear 27. Within the casing 25 is a bevelled pinion 35 meshing with the said gear 27, said pinion being fixed on the upper end of a transmission shaft 36 mounted in a bearing 37 on the casing 25, and also in a bearing 38 on a casing 39 mounted on the frame 90 preferably adjacent the base thereof, said casings 25 and 39 being connected by a shaft casing 40 enclosing the said shaft 36, as clearly shown in Fig. 5. At its lower end the shaft 36 is geared to a shaft 43, as by a bevelled pinion 41 meshing with a bevelled pinion 42 within the casing 39 and fixed upon the driving shaft 43 driven from a suitable source of power, said shaft being preferably the armature shaft of an electric motor 44 deriving current from any desired source. By this arrangement it will be seen that the receiver will be revolved within the receptacle 6 whenever the motor is energized, and the clutch member 30 is in engagement with the clutch member 28 on the gear 27. The receptacle is adapted to contain the liquid with which the material in the receiver is to be treated, the liquid entering and receding from the receiver through the perforations in the cylindrical shell thereof. A movable diaphragm 45 is so mounted and operable that it may be utilized to lift the contents of the receiver toward the opening 11, so that such contents may be lifted out of the liquid and moved into a position adjacent the said opening 11, whereby they may be conveniently removed by the operator through said opening, and also so as to turn over the material or stock being treated, and deposit it in the liquid, and, further, under certain conditions, to be described hereinafter, to squeeze liquid through said material. In the embodiment shown, this diaphragm consists of an arcuate member 45, consisting preferably of a perforated casting

or plate or plates of perforated sheet metal, said member being substantially the same length as the interior of the receiver, as shown in dotted lines in Fig. 2, and of a width approximately one-third of the circumference of the receiver. The bearing members 15 and 20, heretofore described, are provided with extensions 15^a, 20^a, preferably integral therewith, lying on the outer faces of the heads 10 of the receiver and extending radially from said bearing members to a point approximately the circumference of the receiver, as shown in full lines in Fig. 4, and in dotted lines in Figs. 1 and 3. These extensions 15^a, 20^a, are secured 80 rigidly to the heads 10, in any suitable manner, so as to rotate therewith. At their outer ends the members 15^a, 20^a, are each provided with a bearing 46, in which bearings are arranged the ends of a horizontally disposed rock-shaft 47 extending through the interior of the shell of the receiver and at a point closely adjacent the inner face of said shell, as shown in Fig. 3. Upon this shaft 47 is rigidly mounted one end or edge 90 portion of the diaphragm 45. This diaphragm (see Fig. 8) includes spaced sleeves 48 on the shaft 47, said sleeves being connected by a bar 49 integral therewith, and said sleeves being each provided with an 95 arm 50, said arms extending laterally from the shaft 47 and serving to support the perforated plate or plates forming the said diaphragm 45. The sleeves 48 are each secured to the shaft 47 by a tapered pin 51 extending 100 through openings in the said sleeve and transverse openings in the shaft 47, as clearly shown in Fig. 8, or by other suitable means. The shaft 47 is so located, and the diaphragm 45 is so fixed thereon, that the 105 outer convex face of the diaphragm lies against the inner face of the shell of the receiver, as clearly shown in Fig. 3.

On the end of the shaft 47 adjacent the driving mechanism, heretofore described, is 110 fixed one end 52 of a lever 53, the latter carrying on its outer end a laterally projecting pin 54 upon which is rotatably mounted a bearing roller 55 (see Figs. 4 and 5), adapted to be engaged, by means to be 115 hereinafter described, to rock the shaft 47 to swing the diaphragm 45 through the interior space of the receiver.

I will now describe the means for operating the lever 53 to swing the element 45 on 120 its pivot 47. On the end wall 6 of the outer receptacle and inside the latter is arranged and supported a cam bar 56, the latter being pivoted at one end on said wall, as at 57, adjacent one vertical edge of the wall and preferably below the axis of rotation of the receiver, said bar extending upward from its pivot in an inclined direction and above the axis of rotation of the receiver. This 125 cam bar is limited in its downward move- 130

ment by means of a stop 58, against which the under side of the free end of the cam bar is adapted to rest, said stop preferably consisting of a lug or projection fixed to the 5 outer receptacle. The movement of the cam bar upward away from the stop 58 is yieldingly restrained by a contractile spring 59 (see Figs. 1 and 4), one end of which spring is suitably connected, as at 60, to the free 10 end of the said cam bar, and the other end of said spring being anchored to a pin 61 fixed to the said end wall 6 at a point below the cam bar. The cam bar is provided on its under side with a bearing face which is 15 preferably formed adjacent the pivot of said bar with a concave curved portion 62 merging into a convexly curved portion 63 at the central portion of said bar, which portion 63 merges into a concave portion 64 at 20 the outer or swinging end of the bar. The cam bar 56 and its pivot 57 are so located and arranged that the roller 55 on the lever 53 will engage the cam face of the bar 56 inside said pivot after the free end of the 25 element 45 has passed said pivot, thereby causing said element to be swung inwardly toward the axis of rotation, and thereby either throw the contents of the receiver toward the opposite side of the latter and 30 down into the liquid, or squeeze said contents against said opposite side, provided the bulk of the contents is sufficient.

In order to prevent the diaphragm 45 from falling over when its free end passes 35 a vertical line passing through the pivot 47, and also to cause the diaphragm to move outward to its normal outer position adjacent the shell of the receiver, I, preferably, but not necessarily, provide a second 40 cam bar 65, the same being fixed on the said end wall 6 at a point beneath the cam bar 56 in order to provide a passage or space through which the roller 55 passes. The cam bar 65 is located for a major portion 45 of its length with its bearing face substantially parallel to the bearing face of the bar 56, the initial end of this bar 65 being located short of the pivoted end of the bar 56 (as shown in Fig. 4), and the final end being 50 turned away from said bar 56 and directed downwardly, as at 69. The arrangement is such that when the receiver is in the position shown in full lines in Fig. 3, and the receiver is revolved in a counter-clockwise direction, the roller 55 strikes adjacent the pivot 57 and rides against the bearing face of the cam bar 56 until the upper end 55 of the element 45 approximates the vertical, and then upon continued revolution of the 60 receiver, the roller 55 strikes against the cam bar 65 holding said diaphragm in its outer position until said roller 55 passes the center of the receiver, whereupon the continued revolution of the receiver causes 65 the roller to travel between said cam bars

until the roller reaches the part 69, thereby causing the diaphragm 45 to resume its normal position against the inner wall of the receiver. Upon the continued revolution of the receiver, the operation just described is 70 repeated. During this revolution of the receiver the movement of the diaphragm 45 to and from the center of the receiver is automatically controlled by the variable cam 75 56 by virtue of the spring 59 which compensates for variations in load upon said diaphragm resulting from the amount of the material being treated in the receiver. It will be observed that rotation of the receiver 9 will result in tumbling and agitating of the stock and liquor therein effectually dislodging and removing the dirt and foreign matter from the stock, but this action is accelerated by the action of the diaphragm as described. 80

As shown in Figure 3, I may provide the receiver with a flattened wall portion 70, consisting of a perforated curved plate with center of curvature at 47 extending lengthwise of the cylinder from one head to the other, and having one edge portion located adjacent the outer edge of the diaphragm 45, and the other edge portion preferably abutting the cylinder adjacent one longitudinal edge of the opening 11, said flattened 90 portion acting as a slide against which the movable diaphragm 45 operates, and serving to cause the contents of the receiver to be deflected onto said diaphragm. The wall 70 also prevents the goods being treated from falling behind said diaphragm 45. The diaphragm 45, or other parts of the receiver, may be provided with ribs or baffle members 95 71 extending lengthwise thereof and parallel to each other and acting as supports to carry the material being treated along with the member 45 when the latter is on the ascending side of the receiver. Instead of providing the separate element 70, I may construct the receiver, as shown in Fig. 7, in which the same effect is produced by merely flattening one side portion of the cylinder, as indicated at 70^a. The flattened wall portion 70 of cylinder 9 is preferably formed on a curve forming an arc on a radius taken 100 from the center of the pivot 47 of the diaphragm 45, so that the outer end of said diaphragm during the swinging movement of the latter closely approaches said element 70, so that the goods being treated will not 105 pass over the end of the diaphragm 45. 110

In addition to the means for automatically 115 swinging the diaphragm 45 on its pivot toward the center of the receiver, I also provide means for manually swinging or lifting said diaphragm so that the latter may be employed to lift the material being treated out of the wash water or treating liquor and toward the opening 11, so that such material 120 may be conveniently reached when it is de- 125 130

sired to remove the same from the receiver. This means preferably consists of a lifting bar or lever 72 fulcrumed, as at 73, on the wall 6, and extending between said wall and 5 the head 10 of the receiver. This lifting member 72 is arranged so as to swing in a vertical plane intersecting the roller 55, and is rigidly connected to a manual operating lever 74, by means of which the lifting bar 10 72 may be swung on its fulcrum. When the receiver is in substantially the position shown in Figs. 1 and 3, the operator may, by properly swinging the hand lever 74, lift the lower end of the said lever 72 until the 15 end portion thereof strikes the roller 55, and by continuing the swinging movement of said operating lever 74 the lever 72 may then be caused to exert sufficient force upon the said roller 55 and lever 53 to lift the dia- 20 phragm 45 toward the opening to the receiver, for example, to the position shown at α in dotted lines in Figure 3. By this operation the diaphragm 45 may be utilized as a lifting device to lift the goods or material 25 being treated out of the liquid to a position where such goods or material may be conveniently grasped by the operator to remove the same from the receiver. This will be found very convenient, inasmuch as the 30 hands of the operator do not have to be immersed in the liquid in order to remove the contents of the receiver.

In the form shown in Fig. 6, the dia- 35 phragm 45 constitutes a part of the outer shell of the receiver, filling a space 75 there- in. In this form, the free end of the said diaphragm in its outer position rests upon stops 76 on the fixed portion of the shell, and is thereby held against outward movement 40 relative to the shell.

What I claim and desire to secure by Letters Patent of the United States is:—

1. In a machine of the character de- 45 scribed, in combination, a receiver in- cluding a cylindrical drum having a re- ceiving opening leading to an interior compartment and being revolvably mounted to agitate the contents of the receiver, a swinging diaphragm mounted within 50 said receiver eccentrically to the receiver mounting and conforming in contour to the sides of the receiver and in one position lying closely adjacent the inner surface thereof, and manually operable means to move said diaphragm so as to lift the contents of the receiver towards said opening and to hold it in position for convenient re- 55 moval therethrough, the receiver having a curved portion approximately concentric 60 with the mounting of said diaphragm and lying adjacent the swinging end thereof.

2. In a washing machine, in combination, 65 a receiver having a shell with an opening leading to an interior compartment for containing stock to be treated, said receiver be-

ing mounted for operation to agitate said stock, a lifting member mounted in said receiver, conforming in contour to said shell and in one position lying closely adjacent said shell remote from said opening, and means to move said lifting member to lift the stock contained in the receiver toward said opening and to hold it in lifted position. 70

3. In a machine of the character de- 75 scribed, in combination, a revoluble cyl- 80 inder forming a receiver having a re- ceiving opening, a swinging lifting mem- ber mounted in said receiver, means to move said lifting member to lift the stock contained in the receiver toward said receiving opening and to support it in lifted position for convenient removal through the opening, and means for operating said lifting member to agitate said stock 85 and to squeeze it against a wall of the re- 90 ceiver.

4. In a machine of the character de- 95 scribed, in combination, a receiver having a substantially closed compartment for the re- 100 ception of stock and a receiving opening leading thereto, said receiver being mounted for movement to agitate said stock, a lifting member positioned within said receiver to lie at one side of said compartment out of the body thereof, and means to operate said lifting member to move said stock towards said opening and to support it in position for convenient removal therethrough. 105

5. In a washing machine, a receiver 110 having an opening, a diaphragm pivoted within said receiver, a lever connected to said diaphragm and extending outside the receiver, and a manually operable lever co- 115 operable with said first named lever to move said diaphragm to lift the contents of the receiver toward said opening.

6. In a washing machine, a revoluble re- 120 ceiver having an opening, a swinging dia- phragm in said receiver, means cooperable with said diaphragm to automatically swing said diaphragm during revolution of the receiver, and manually operable means to move said diaphragm to lift the contents of the receiver toward said opening. 125

7. In a washing machine, a revoluble re- 130 ceiver having an opening, a diaphragm pivoted within said receiver, a lever connected to said diaphragm and extending outside the receiver, means cooperable with said lever to automatically swing said diaphragm during revolution of the receiver, and manually operable means cooperable with said lever to move said diaphragm to lift the contents of the receiver toward said opening.

8. In a washing machine, a revoluble re- 135 ceiver having an opening, a diaphragm pivoted within said receiver, a lever connected to said diaphragm and extending outside the receiver, means including a yielding cam bar cooperable with said lever to automatically

swing said diaphragm during revolution of the receiver, and manually operable means co-operable with said lever to move said diaphragm to lift the contents of the receiver 5 toward said opening.

9. In a machine of the character described, in combination, a receiver having a compartment for the reception of stock under treatment and a receiving opening leading thereto, a combined agitating and lifting member within said compartment, means to agitate said stock by simultaneous oscillation of said member and movement of said receiver upon said supports, and means 15 for independently operating said member to lift said stock toward said receiver opening.

10. In a machine of the character described, in combination, a revolute drum 20 providing a receiver having a substantially closed compartment for the reception of stock and a receiving opening leading thereto, a diaphragm mounted for swinging movement within said compartment, means 25 external of said revolute drum for operating said diaphragm to agitate said stock, and means external of said drum for operating said diaphragm to lift said stock toward said opening and support it in convenient position for removal therethrough.

11. In a machine of the character described, in combination, a receptacle for a treating fluid, a drum revolutely mounted in said receptacle and providing a 35 substantially closed receiver having a compartment for the reception of stock and a receiving opening leading thereto, a swinging diaphragm mounted within said compartment and conforming in contour to the walls of said receiver and positioned to lie at one side of said compartment and means to move said diaphragm and lift said stock toward the receiver opening and support it in position for convenient removal therethrough.

12. In a washing machine, in combination, a revolute receiver having a compartment for the reception of stock and an opening leading thereto, a rock shaft extending 50 longitudinally of said receiver, a diaphragm rigidly mounted on said shaft and in one position lying substantially wholly at one side of said compartment and conforming in contour to the walls thereof, means for automatically rocking said shaft during revolution of the receiver, and manually operable means independent of said first mentioned means for rocking said shaft.

13. In a washing machine, in combination, a receiver having a compartment for the reception of stock and an opening leading thereto, a rock shaft extending longitudinally of the receiver, a diaphragm rigidly mounted on said rock shaft and in one 65 position lying substantially wholly at one

side of said compartment and conforming in contour to the walls thereof, a lever rigidly mounted on said rock shaft, and manually operable means co-operating with said lever to rock said shaft to swing said diaphragm 70 to lift the contents of the receiver toward said opening.

14. In a washing machine, in combination, a revolute receiver having a compartment for the reception of stock and an opening leading thereto, a rock shaft extending longitudinally of the receiver, a diaphragm rigidly mounted on said shaft and in one position lying substantially wholly at one side of said compartment and conforming in contour to the walls thereof, a lever rigidly mounted on said rock shaft, means for automatically rocking said shaft during revolution of the receiver, and manually operable means co-operating with said 80 lever to swing said diaphragm to lift the contents of the receiver toward said opening.

15. In a washing machine, in combination, a revolute receiver having a compartment for the reception of stock, comprising a shell and heads and having an opening leading thereto through said shell, a rock shaft extending longitudinally of the receiver and mounted in bearings in said 90 heads, a diaphragm mounted on said shaft and in one position lying substantially wholly at one side of said compartment and conforming in contour to said shell, a lever on one end of said shaft, cam means adapted 95 to be engaged by said lever during one period of a revolution of said receiver to rock said shaft, and manually operable means co-operating with said lever when out of engagement with said cam means for operating said diaphragm.

16. In a washing machine, in combination, a revolute receiver having a compartment for the reception of stock, comprising a shell and heads and having an opening 100 leading to said compartment, a rock shaft extending longitudinally of the receiver and mounted in bearings in said heads, a diaphragm rigidly mounted on said rock shaft and in one position lying substantially wholly at one side of said compartment and conforming in contour to said shell, a lever on one end of said rock shaft, a yielding cam bar adapted to be engaged by said lever during one period of a revolution of said receiver to rock said diaphragm, and independent manually operable means co-operating with said lever to rock said diaphragm.

17. In a washing machine, in combination, a revolute receiver having a compartment for the reception of stock having a shell with heads and an opening leading to said compartment, a rock shaft mounted in bearings on said heads, a diaphragm rig- 125

idly mounted on said shaft and in one position lying substantially wholly at one side of said compartment and conforming in contour to said shell, a lever on one end of 5 said shaft, a yielding cam bar pivoted at one end and adapted to be engaged by said lever during one period of a revolution of said receiver to swing said diaphragm, a second cam co-operating with said lever to 10 swing said diaphragm in an opposite direction, and independently operable means co-operating with said lever to swing said diaphragm.

18. In a washing machine, in combination, a revoluble receiver having a compartment for the reception of stock and an opening leading thereto, a rock shaft mounted in the receiver, a diaphragm mounted on said rock shaft, a lever mounted on said 20 shaft, a yielding cam member for engaging with said lever to move said diaphragm for agitating and squeezing said stock, and a rigidly mounted cam member adjacent said first mentioned cam member for co- 25 operating with said lever to return said diaphragm to original position.

19. In a machine of the character described, in combination, a receiver including a revolubly mounted drum having a compartment for the reception of stock, a swinging diaphragm mounted within said compartment eccentrically to the drum mounting and adapted for agitating said stock, and the inner surface of said drum adjacent the free end of the diaphragm being 30 formed to lie closely adjacent thereto 35

throughout its travel so as to prevent the free edge of said diaphragm from injuring said stock and to prevent the diaphragm from being obstructed in its movement by 40 the stock.

20. In a washing machine, in combination, a receiver for stock having a shell and end heads, bearings for the receiver on said heads having laterally extending arms, and 45 means mounted in said arms for agitating said stock.

21. In a washing machine, a receiver having an opening, a swinging diaphragm in said receiver conforming in contour to 50 the shell of the receiver and in one position located closely adjacent the inner surface of said shell, and manually operable means to move said diaphragm to lift the contents of the receiver toward said opening, the receiver having a wall portion adjacent the swinging end of the diaphragm, said wall portion being curved on a radius taken on the center of swinging movement 55 of said diaphragm.

22. In a washing machine, a receiver, a swinging diaphragm in the receiver, means for swinging said diaphragm, said receiver having a wall portion adjacent the swinging end of the diaphragm, said wall portion being curved on a radius taken on the center of swinging movement of said dia- 60 phragm.

In testimony whereof I have hereunto signed my name.

FREDERIC HENRY EHNTS.
